UNITED STATES PATENT OFFICE.

FRANCIS A. WALSH, OF CHICAGO, ILLINOIS.

SEAMING-MACHINE.

SPECIFICATION forming part of Letters Patent No. 277,962, dated May 22, 1883.

Application filed January 15, 1883. (No model.)

To all whom it may concern:

Be it known that I, FRANCIS A. WALSH, of Chicago, in the county of Cook and State of Illinois, have invented certain new and useful improvements in Seaming-Machines; and I hereby declare the following to be a full, clear, and exact description thereof, which will enable others skilled in the art to which my invention relates to make and use the same, reference being had to the accompanying drawings, forming a part hereof, and in which—

Figure 1 represents a side elevation of my improved machine ready for work, with a part of the cone-pulley broken away. Fig. 2 is a front elevation taken on and back of the plane $x\ x$ of Fig. 1. Fig. 3 is a plan view of the bracket b , the plate c being removed, and showing an end view of the bed-plate a and rod c^2 . Fig. 4 is a plan view of the bracket g^4 and the parts operating in or nearly in the same plane with it, the parts above being removed. Fig. 5 represents a profile of the circumference of the wheel or cam e . Fig. 6 shows a plan view of the cam e and gear-wheel dotted underneath it, the worm d^2 and its shaft, crank, levers, and spring to operate the rack h^3 . Fig. 7 represents a plan view of the rod g and its operating-cam e^3 and a part of the bracket g^4 , which latter is also shown in dotted outline in a position it is moved into by the rod g . Fig. 8 shows a central longitudinal sectional elevation of the gear-wheel d^6 and its shaft and spring in full. Fig. 9 shows a cross-section of the shaft f^7 , taken in the plane $y\ y$, Fig. 4, and its rollers $f^8\ f^9$. Fig. 10 shows the end of the shaft f^7 with its roller f^{10} in side elevation. Fig. 11 represents an elevation of a can-body provided with an end ready for putting into the machine. Fig. 12 shows the cover of the can with its burr or flange turned against the body of the can. Fig. 13 shows the position of the can, shaft, and its rollers $f^8\ f^9$ after the operation shown and described in Fig. 12. Fig. 14 shows the partly-completed double seam and position of shaft f^7 and rollers thereto at the time that the bracket g^4 may be turned so as to draw the rollers $f^8\ f^9$ out and away from the seam at that position. Fig. 15 shows the farthest position that the shaft f^7 may turn to from that shown in Fig. 14, and the position of the partly-finished double seam at that po-

sition of the shaft f , and also the final position (shown dotted) of the can when the roller f^{10} finally completes the double seam. Fig. 16 shows the final completion of the double seam by the roller f^{10} . Fig. 17 represents a plan view, and Fig. 18 a side elevation, of the attachment to the seaming-machine, used either for beading cans singly, or for both seaming and beading them singly, or for beading a series of cans with ends already seamed to one end of the can-body, or for both beading and seaming them at the same time. Fig. 19 shows the construction of the plate c^8 as formed when used in connection with the mandrels k^3 when it is desired to make the end without or but a slight countersink after the double seam is finished, the plates c and c^8 , mandrel k^3 , and can k^4 being shown in a vertical central section, and the rollers $f^8\ f^9$ having hold of the can and its cover, ready to turn down the parts so held into a double seam, and the opposite side showing the seam finished.

Like letters of reference indicate like parts.

My invention consists in the construction of the various improved parts of a double-seaming machine as herein shown, so that it will now automatically clamp the can-body and one of its ends together between two adjustable revolving chucks, with which the can revolves on its axis, and while so turning one end is united to the body with a double seam by means of automatically-operating mechanism, which consists of a single roller that first turns down the burr or flange of the cover against the body of the can, and next of a pair of rollers attached to a reciprocally and partially revolving shaft, which then turn down the can-body and wall of the countersunk part of the cover over and so near against the can-body that the seam may then finally be pressed down against the can-body by the same roller first mentioned above; and said reciprocating shaft is so connected with other mechanism that it may be arrested in its action on the partly-finished double seam and caused to leave it standing at right angles to the body of the can, or at any other desired angle; and my invention also further consists in attaching and operating simultaneously with said devices mechanism which will bead the can-bodies, after which the cans in either case are

automatically released from the chucks, ready to drop or be taken out of the machine, all as hereinafter more fully described.

In the drawings, A represents the standard 5 of the machine, to the front of which is attached a bed-plate, a, upon which slides a bracket, b, carrying a disk, c, which spins freely on a spindle, c'. Said bracket b is firmly attached to a rod, c'', at any desired elevation, 10 by means of a set-screw, c''. The rod c'' extends upward through the bracket or bearing c', in which it works freely, and yoke c'', in which it is held and minutely adjusted by the double nuts c''. The other end of the yoke c'' has 15 a long hub which slides freely upon the shaft d, and at or near the center of said yoke is a roller, c'', the axis of which is parallel with a central vertical plane through the yoke. Said roller runs upon the upper side of a wheel, e, 20 the upper side of which is formed into an irregular cam, the developed profile of which is shown in Fig. 5. The wheel e is firmly attached to the shaft d, and immediately below, on the same shaft, is attached a worm-wheel, e', gearing 25 into the worm d'', fixed on the shaft d''. Said shaft d is carried in a bracket, d'. To the outer end of the shaft d'' are attached the cone-pulleys d'', from which the machine receives its motion, and to the other end of said shaft d'' 30 is attached a bevel-pinion, d'', meshing into the wheel d'', which, with its shaft and spring, is shown more fully in an enlarged sectional view in Fig. 8. Said gears d'' d'' and the worm d'' and worm-wheel e' are so constructed that 35 while the cam e is making one revolution the wheel d'' is making somewhat more than three revolutions, for the upper chuck or plate, c'', is attached to its shaft, and this determines the number of revolutions the can-body makes for 40 the different operations while making the double seam. The shaft c'' slides freely up and down in the bearings in the arms d'' d''. The long hub of the wheel d'' is turned down, so as to form a shoulder resting on the arm d'', 45 while the part below the shoulder plays in the bearing in said arm, and is provided on its inside with a groove in which plays a feather, d'', attached to the shaft c''. The upper part of the hub of said wheel is chambered or bored 50 out to make room for a spring, c'', to play freely. Said spring rests upon a collar resting upon a shoulder of the shaft c'', and the upper end of said spring bears against the arm d''. 55 On the shaft d, below the bearing d', are attached cams c'' c'', and to the end of said shaft a crank, e''. The cam c'' is provided with spurs or wipers f f'' upon its circumference, which work against the spur or toe f', attached to the 60 upper side of the rod f''. Said rod works on the under side of the cam c'', and is provided with a slot, f'', through which the shaft d passes, and which serves to guide it in its operation.

To the outer end of the rod f'' is attached a 65 post, f'', of which the lower end is provided with a collar and a set-screw, f''. Said collar slides freely on the shaft f'', and is fixed on it

at any desired place by the set-screw f''. The shaft f'' passes through and its center coincides with that of the outer journal of f'', and 70 carries on its inner end a roller, f''. Said roller is moved in and out to and from the can, first, to turn down the flange u of the cover, as shown in Fig. 12; second, to complete the partly-formed double seam, as shown in Fig. 16, 75 after the rollers f'' f'' have first turned it into the form or position shown in Fig. 15. When the seam is completed as far as can be done by the rollers f'' f'' the roller f'' has to be passed out from its position under the seam, 80 which may be done either by moving the shaft f'' or the roller f'' on the shaft down below the seam, or else by lifting the can up into the position shown dotted in Fig. 15, and which in this case is accomplished by the cam e. The 85 spurs f f'' draw the roller against the can, and the spring f'' throws it back as soon as released from said spurs.

The rod g surrounds the lower end of the cam c'', which is provided with a single wiper 90 or spur, g'', which works against the toe or projection g' on the rod g for the purpose of throwing the bracket g', turning on the pin g'', around into the dotted position shown, and thus withdraw the rollers f'' f'' from the can. When the 95 seam is brought at right angles to the can-body, as shown in Fig. 14, and when the spurs g' g'' have passed each other, the spring g'' will throw said bracket into its proper position again. 100

To the under side of the rod surrounding the cam c'' is attached a plate, e'', (shown dotted in Fig. 7,) provided with a slot, g'', through which the shaft d passes, and which serves to guide the rod g. 105

To the crank-pin e'' is attached a rod, h, provided at its outer end with a slot, i, in which plays a pin or stud, i'', attached to the rod h''. The rod h'' works on a stud, i'', at or near its center, and around the stud i'' is wound a 110 spring, i'', with a tension tending to throw the rod h inward, as indicated by the arrow. The outer end of the bar h'' is also provided with a slot in which plays a stud, i'', fixed to the rack h''. Said rack passes on the under side of 115 and meshes with the pinion h'', adjustably attached to the shaft f''. 120

The mechanism to bead the cans is constructed substantially as follows: Directly in front of the seaming-machine is fixed a post, 120 upon which revolves in a horizontal plane a disk or spider, k', provided with equidistant holes k'', into which are placed mandrels k'', of a size to fit into the cans to be beaded. A can, k'', is shown over such a mandrel, (shown in 125 dotted outline within,) and the beading-roller k'' just relieved from it. Said mandrels extend to the end of the can to support the head for the purpose of turning over all or nearly all of the wall of the countersink of the cover into 130 the double seam, and thereby make the can flat-bottomed.

When it is not desirable to work the countersink out of the ends, as just described, but

simply to bead one end of the can, a short mandrel, k^6 , with a flange, k^8 , to rest the can on, is provided. The journal of said mandrel is provided with a conical socket in its lower end 5 and at its center, into which fits the corresponding conical point of the pin c' , upon which the mandrel is carried and turns during the operation of beading and seaming. Mandrels k^3 k^9 are both made to nearly fit the interior of the can, room enough being left so that the can 10 may be lifted from the mandrel after being beaded. The mandrel k^9 is intended, as shown, for a much smaller can than k^3 , and is shown in its proper place in opening k^2 of spider. Of course mandrels of only one kind and size can 15 or are to be used at the same time. The sides of the can will yield sufficiently to the pressure of the roller k^5 to form a bead. The lower end of the can is supported on the flange k^8 , 20 with which all the mandrels must be provided. The plate c^8 should be made as thin as possible and its edge beveled down sharp, as shown in Fig. 19, so that the rollers f^8 f^9 may take hold and begin to form the double seam at or 25 nearly at the base of the wall of the countersink, so that when the double seam is completed the countersink will practically be out of the end of the can, or so as to leave but a slight mark. The beading-roller k^5 turns 30 freely in a lever, k^6 , pivoted to the horn k^7 of the bracket b , so as to work in a horizontal plane, and is caused to work against the cans by the wedge m , attached to the bed-plate a by the set-screw m^2 , as the bracket b rises. 35 To the side of the post A is attached a spring, l , provided with a rounded projection, k^9 , to fit into the notches k^8 , and of such a length that when the spur k^9 is in a notch k^8 it will hold the conical socket of the mandrel directly over 40 the point of the pin c' .

To the under side of the disk k' is attached a ratchet-wheel, l' , into which works a ratchet, l^2 , on a lever, l^3 , pivoted at l^4 , and so proportioned and adjusted to the lower end of the 45 rod c^2 that every time the rod c^2 descends it operates the lever l^3 and causes the disk k' to turn around, pulling the spring l out of the notch k^8 , and catching in the next succeeding one, and thus stop the next mandrel at its 50 proper place. The rod c^2 , yoke c^5 , and bracket b have sufficient weight to turn the spider k' , which is made light and so as to turn easily; but should the pressure on the lever l^3 thus obtained not be great enough, the bracket b 55 may be made heavier or a weight added to it, or a spring attached to it from the floor or base of the machine.

o represents a counting apparatus, from which projects a rod or lever, o' , which operates its mechanism, and which may be operated by the spur o^2 on the shaft d , and which turns around once; or it may be operated by the yoke c^5 , which rises once for every can seamed.

65 The arrows indicate the direction of motion of the different parts.

The operation of the foregoing-described ma-

chinery is as follows, to wit: A chuck or plate, c^8 , of a size to fit into the countersunk end of the cans to be operated upon, is first attached 70 to the lower end of the spindle c^9 . Next the disk c is adjusted to the proper point to suit the height of said cans, and the roller f^{10} is set so as to work properly on the rim u of covers of given diameter. When all is ready a cover, 75 p , is placed upon the can q , which is then placed centrally upon the plate or table c and the treadle j pressed down. By the arrangement of rods and levers shown this will raise the roller c^7 out of the notch k^5 , and thus relieve the spring i^3 , wound around the post i^2 , and cause the shaft d to turn, and the worm d^2 , which was heretofore playing in the blank r , to engage with the worm-wheel, which then turns the shaft until the roller c^7 again 80 drops into the notch k^5 . When the cam-wheel e is thus made to turn, the roller c^7 first runs over the level s^3 , then up the inclined plane s , and thereby lifts the yoke c^5 , and with it the attached rod c^2 and bracket b , and thus 85 drives the head p of the can against the plate c^8 , and thereby clamps the can tightly between the plates c and c^8 , which now, by frictional contact with plate c^8 , will revolve, the shaft c^9 rising against the pressure of the spring c^{10} . 90 The can is automatically adjusted and begins to revolve as the roller c^7 runs up the inclined plane s . By the time that roller c^7 arrives on the level s^3 one of the spurs or wipers of the cam e^2 has engaged with the spur f^4 , attached 95 to the rod f^2 , and drawn the roller f^{10} against the rim of the can-cover and caused it to turn down said rim against the body of the can, as shown in Fig. 12; the spur f^4 being made long enough so that the can may revolve once while 100 the roller f^{10} operates, after which it is released and pushed back out of the way by the spring f^3 . At any time after the roller f^{10} has turned down a sufficient part of the rim of the cover, as shown in Fig. 12, the rollers f^8 f^9 may begin 105 to operate. The can and cover are lifted up by the adjusted bracket b between the rollers f^8 f^9 , as shown in Fig. 13, so that said rollers may operate at the proper point to form the double seam. The rollers f^8 f^9 are operated by the crank e^3 and the intermediate parts, h k^8 k^9 . As the action of the spring i^3 is to 110 throw the rack h^3 outward, it will cause the shaft f^7 to turn so as to throw the roller f^9 down 115 snugly upon the plate c^8 , and hold it there during the time that part of the rim of the cover is being turned down. While this is being done the pin i' plays in the slot i . After the crank-pin has passed sufficiently beyond the other side of the center of the shaft d so 120 that the end of the slot will play against the pin i' it begins to push the rack h^3 in the opposite direction, and thus turn the shaft f^7 outward from the position shown as first assumed in Fig. 13 successively into that shown 125 in Fig. 14, and finally into that shown in Fig. 15. By the time the shaft f^7 has turned into this last position the roller c^7 has reached the end of the plane s^3 , and at this point suddenly 130

lifts up onto the plane s^2 of the cam e and lifts with it the plate c , and thus forces the partly-formed double seam to pass up and out from between the rollers f^8 f^9 into the position shown dotted in Fig. 15, (this part has been more fully and completely explained in a former application referring more particularly to this part,) and simultaneously the spur or wiper f^{10} comes in contact with the toe f' and again 10 pushes the roller f^{10} in contact with the can, (said roller being made high or long enough,) and thus finishes the double seam by turning it down against the body of the can, as shown in Fig. 16, and by the time the wheel e has 15 thus made one complete revolution the roller c^7 has arrived at and again dropped into the notch h^5 and stopped the revolution of the shaft d , and this also drops the table c , so that the can may be taken out from between the plates c^8 c . When it is desired to work continuously and more rapidly, the lever j^2 may 20 be set by the nut j^4 so that the rod c^2 will not permit the roller c^7 to drop to the bottom of the notch h^5 . The spring i^3 will therefore cause 25 the worm-wheel e' to pass the gap r and instantly re-engage the worm-wheel with the worm d^2 , while the roller c^7 runs on the short plane s^3 , thereby producing a continuous and uninterrupted motion of said machinery.

30 Instead of having the notch r in the worm-wheel e' for the purpose of stopping the machinery at each completion of a can, a Mason friction-clutch may be placed into the cone-pulley d^4 and operated through a rod and lever by the falling yoke e^5 of rod e^2 .

When it is desired to form what may be called a "partial double seam," such as is shown formed on the can in Fig. 14, the necessary mechanism to be added to that already described for forming the complete double seam consists of a cam, e^3 , on shaft d , formed as shown in Fig. 7, which operates a rod, g , one end of which is formed into a ring surrounding said cam e^3 , and has on one side of its inner circumference a spur or toe, g' , against which the wiper g^2 strikes and causes the rod g to pull the bracket g^4 around into the position shown in dotted outline on the bolt or center g^5 , the spring e^6 resisting and throwing it back into its first position as soon as the spur g^2 and toe or spur g' have passed each other.

To the under side of the rod surrounding the cam c^3 is attached a plate, e^4 , (shown dotted in Fig. 7,) which is provided with a slot, g^7 , through it to pass the shaft d for the purpose of guiding the rod g in its longitudinal motion. The plate e^4 rests on the hub of the crank e^5 . The spur g^2 and toe g^4 are so placed as to pull the bracket g^4 into the dotted position at the instant that the partial double seam is formed, as already stated, and shown in Fig. 14, and thus throw the rollers $f^8 f^9$ out and away from the seam, while all the already-described parts and said rollers $f^8 f^9$ go through their full motion, so as to finally release the can from its chucks.

It is also evident in this case that the mechanism used to throw the rollers f^8 f^9 from the can may be formed in many other ways; but I have here described such as is best adapted to the general construction shown, and the same may be said in regard to the cam-wheel e . Many other forms of lifting device might be shown to lift the can at fixed and positive intervals to exact previously-determined points. The mandrels k^3 k^0 turn freely in their bearings in the plate k' , and are raised by the center c' when the cans are either seamed or beaded. The roller f^{10} may be arranged in any other manner desired, or even attached to a lever and worked by hand. The bolt c' may be lowered in its socket, the plate c removed, and the spindle of a mandrel, k^0 , held in the bracket b , so that it may turn on the bolt or spindle c' , and cans placed on said mandrel may then be beaded without the use of the spider and its attached mechanism. The rod c^2 may have an arm projecting from it, to which the roller c^7 is attached, as the rod c^2 is clamped by the bolt c^3 , so that it cannot turn around in its bearings and operate quite as well as with the yoke; or the roller c^7 may be attached directly to the rod c^2 , in either case adjustably attached; but the way shown is preferable because it diminishes friction.

What I claim is—

1. The rocking rollers or formers $f^8 f^9$, operating in a plane passing through the axis of the can, in combination with the reciprocating roller f^{10} , substantially as specified. 100
2. The plates $c c^8$, rocking shaft f^7 , rollers $f^8 f^9 f^{10}$, and means, substantially as described, for operating said parts. 105
3. The shaft c^9 , plate c^8 , adjustable plate c , rocking shaft f^7 , rollers $f^8 f^9 f^{10}$, and mechanism for operating said parts, substantially as specified. 110
4. In combination with the rocking rollers $f^8 f^9$, the plates $c c^8$, cam e^3 , rod g , and pivoted bracket g^4 , substantially as specified. 115
5. The longitudinally and automatically reciprocating shaft c^9 , plates $c c^8$, shaft d^3 , gears $d^5 d^6$, worm d^2 , worm-wheel e' , shaft d , cam e^3 , rod g , shaft f^7 , rollers $f^8 f^9 f^{10}$, and bracket g^4 , substantially as specified. 120
6. The cam e and shaft d , in combination with the yoke c^5 , rod c^2 , adjustable bracket b , feathered shaft c^9 , gear d^6 , and plates or chucks c^8 , substantially as specified. 125
7. The worm d^2 , worm-wheel e' , shaft d , yoke c^5 , rod c^2 , bracket b , parts $j j' j^2 j^3 j^4$, shaft c^9 , plates $c c^8$, rocking shaft f^7 , rollers $f^8 f^9 f^{10}$, parts $h h' h^3 h^4$, and connecting means for rotating the worm d^2 and shaft c^9 , substantially as specified. 130
8. The worm d^2 , worm-wheel e' , shaft d , cam e , yoke c^5 , rod c^2 , bracket b , parts $j j' j^2 j^3$, shaft c^9 , plates $c c^8$, rocking shaft f^7 , rollers $f^8 f^9$, parts $h h' h^3 h^4$, and connecting means for rotating the worm d^2 and shaft c^9 , substantially as specified. 135

9. In combination with a seaming-machine having a longitudinally reciprocating and re-

volving shaft, c^9 , chuck c^8 , and adjustable bracket b , provided with pin c' , lifted and dropped by automatically-acting parts, mechanism for beading cans, consisting of a beading-roller and mandrels carried upon a horizontally-revolving table, and a lever and pawl connected to said automatically-operating parts, substantially as specified.

10. In combination with the rod c^2 and lever l^3 , the plate or spider l^4 , mandrels h^3 , spring l , roller h^6 , wedge m , and bracket b , provided with pin c' , and plate c^8 , substantially as specified.

11. The cam-wheel e , yoke c^5 , revolving adjustable and automatically-adjusting plates c^8 , and mechanism, substantially as specified, whereby said cam-wheel e may at pleasure have a continuous or intermittent motion.

12. The longitudinally and automatically reciprocating and revolving shaft c^9 and plate c^8 , in combination with the adjustable bracket b , provided with bolt or spindle c' , and mandrel and beading-roller, substantially as specified.

13. The gears $d^5 d^6$, shaft c^9 , plate c^8 , cam e , roller c^7 , rod c^2 , arm or bracket b , adjustable plate c , rocking shaft f^7 , rollers $f^8 f^9$, and mechanism to operate said parts, substantially as specified.

14. The cam-wheel e , provided with notch h^5 , and planes $s s' s^2 s^3$, and rod c^2 and roller c^7 , in combination with the revolving and automatically-adjusting plates c^8 and intermediate mechanism to operate the same, substantially as specified.

15. The clamping-plates c^8 , shafts c^9 and d^3 , pulley d^4 , worm d^2 , worm-wheel e' , cam e , shaft d , rocking shaft f^7 , rollers $f^8 f^9$, and c^7 , rod c^2 , lever j , and the connected means for giving to plate c and shaft f^7 intermittent or continuous motion, substantially as specified.

16. The gearing $d^5 d^6$, shaft c^9 , disk c^8 , adjustable disk c , lever j , rod c^2 , roller c^7 , cam e , shaft d , rocking rollers $f^8 f^9$, and the connected means for rotating the gear d^5 and shaft d , substantially as specified.

17. The gearing $d^5 d^6$, shaft c^9 , disk c^8 , bracket b , disk c , cam e , shaft d , roller c^7 , rod c^2 , rocking shaft f^7 , rollers $f^8 f^9$, and connected means for rotating the gear d^5 and shaft d and rocking the shaft f^7 , substantially as specified.

18. The automatically-clamping plates c^8 , shaft c^9 , gears $d^5 d^6$, shaft d^3 , worm d^2 , worm-wheel e' , shaft d , cam e , rocking shaft f^7 , roll-

ers $f^8 f^9$, and mechanism connecting shafts d and f^7 , substantially as specified.

19. The shaft c^9 , plate c^8 , adjustable plate c , rocking shaft f^7 , rollers $f^8 f^9$, and means for operating the parts c and f^7 , substantially as specified.

20. The plates $c c^8$ and mechanism for causing them to grasp and rotate a can, in combination with the rocking and horizontally-swinging rollers $f^8 f^9$, substantially as specified.

21. The plates $c c^8$ and mechanism for causing them to grasp and rotate a can, in combination with the rocking and horizontally-swinging rollers $f^8 f^9$ and reciprocating roller f^{10} , substantially as specified.

22. The plates $c c^8$ and mechanism for causing them to grasp, turn, and release a can, in combination with the rocking seaming-rollers $f^8 f^9$ and reciprocating roller f^{10} , substantially as specified.

23. In combination with a seaming-machine having a reciprocating shaft, c^9 , plate c^8 , adjustable bracket b , provided with pin c' , and lifted and dropped by automatically-operating parts, mechanism for beading, consisting of beading-roller and mandrels upon a horizontally-revolving table, and lever to turn said table, actuated by said automatically-operating parts, substantially as specified.

24. The plates $c c^8$ and mechanism for causing them to grasp, turn, and release a can, in combination with the rocking seaming-rollers $f^8 f^9$, and mechanism by means of which said parts may have continuous or intermittent motion, substantially as specified.

25. In combination with a seaming-machine having the plate c^8 and spindle c' , adapted to rise and fall, mechanism for beading, consisting of a reciprocating beading-roller and mandrel operated by mechanism substantially as specified.

26. In combination with a seaming-machine having plate c^8 and spindle c' , lifted and dropped by automatically-acting parts, mechanism for beading, consisting of a beading-roller and mandrel or mandrels carried upon a revolving table operated by mechanism substantially as specified.

FRANCIS A. WALSH.
